J. LOTH

METHOD OF MANUFACTURING ARTIFICIAL LIMBS AND SIMILAR DEVICES

Filed Nov. 11, 1927

Inventor:
Julius Loth
by *J. Loth*
attorney

UNITED STATES PATENT OFFICE.

JULIUS LOTH, OF KOSLIN, GERMANY.

METHOD OF MANUFACTURING ARTIFICIAL LIMBS AND SIMILAR DEVICES.

Application filed November 11, 1927, Serial No. 232,622, and in Great Britain August 19, 1927.

The present invention relates to improvements in or modifications of the invention claimed in copending application Ser. No. 202,025.

5 The invention described in the said co-pending application relates to a process of manufacturing artificial limbs and like appliances whereby a model is made of the respective limb to which the artificial appliance is to be matched, such model being covered with a layer of so-called liquid wood. As soon as this layer has set, it is fixed by means of any suitable material such as wood, metal, vulcanite fibre, leather and the like 10 to the actual shell representing the true form of the leg.

This present invention constitutes a further improvement of the said co-pending application and refers to an extremely simple 20 process of affixing the shell made of liquid wood to the limb.

According to this invention, the outer shell of the artificial limb is provided with apertures, a second layer of liquid wood is 25 applied to the shell made of liquid wood as soon as the first layer has set, whereupon the shell made of liquid wood is pressed into the principal or outer shell. The liquid wood thereby penetrates into the apertures 30 of the outer shell and by setting forms a solid unit which will not slip. Any part or aperture possibly left out in the lower end of the inner shell may be filled in with resin or the like.

35 The accompanying drawing gives a possible illustration of part of an artificial limb as constructed by the inventor.

As in the said co-pending application, so is *a* the plaster of Paris impression made in 40 the usual way of the stump of the lower part of a leg. This impression is then covered with a layer *b* of liquid wood as described in the said co-pending application and is allowed to set thereby forming a shell around 45 the stump impression. This shell *b* may be closed at its lower end, as described in the co-pending application, or it may be left open in such manner as to allow the point of the stump to protrude. This latter method 50 will be used in cases where the point of the stump should not receive any pressure. The outer shell i. e. the actual artificial limb is indicated at *c* and may consist of any desired material such as leather, metal, wood, 55 vulcanite fibre and the like.

According to the invention, the outer shell

is provided with apertures *d* at least at that part where the inner shell *b* is to be fitted but these apertures are provided for all over the artificial limb *c* and not less than the 60 heights of the inner shell *b*. These apertures *d* as shown in the drawing may be continued below the shell *b* but they would only constitute a reduction in the weight of the whole limb and not serve to fulfill the purpose of the present invention. 65

A second layer *e* of liquid wood is painted upon the shell *b* as soon as the one upon the stump has set whereupon the shell *b* is pressed into the outer shell *c* while that layer is still 70 liquid. This causes the material *e* which is still in a liquid state to extend into the apertures *d* of the outer shell *c* thereby forming when set, a solid mass *b* on the one hand, and a great number of plugs the size of the apertures *d* with a solid hold, on the other hand, thereby connecting shells *b* and *c* by a firm 75 and insoluble mass. In a case when the stump in its lower part is exceptionally pointed, a proportionally large empty space may appear 80 between the outer shell *c* and shell *d* thereby creating a gap. This gap, according to the invention, may be filled with any resinous matter, preferably an easily dissolved resin *f*, thus connecting shell *b* or material *e* on the one 85 hand, and by extending into apertures *d* contributes to the solidification of shell *b* and shell *c*.

Upon fixing shell *b* into shell *c* and upon consequent setting of the matter *e*, the impression *a* of the stump is eliminated by means of breaking it to pieces. The material *b* is then covered on the inner side with any desired substance or a coat of paint. 90

By "liquid wood" is meant the material 95 described in the said co-pending application consisting of finely dessicated wood, cork, shaving, or the like in connection with a binder. The binder may be for instance a glue or it may be nitrated cellulose, or a similar material that has been dissolved in acetone or acetate and may have other ingredients as well. Similar liquid wood is sold for instance under the trade mark "Necol". 100

Having now particularly described and ascertained the nature of my said invention and in what manner the same is to be performed, I declare that what I claim, is:— 105

1. The method of manufacturing artificial limbs and similar devices, consisting in producing a copy of the respective body portion, 110 covering said copy with a layer of so-called

liquid wood, letting this layer solidify, applying to it a further layer of liquid wood and inserting the thus obtained shell into an outer main shell provided with apertures 5 while the second mentioned layer still is in a liquid state in such a manner as to extend the liquid wood into the apertures of the outer shell thus forming a solid unit of the two shells when it has set.

10 2. The method of manufacturing artificial limbs and similar devices, consisting in producing a copy of the respective body portion, covering said copy with a layer of so-called liquid wood, letting this layer solidify, applying to it a further layer of liquid wood, inserting the thus obtained shell into an outer main shell provided with apertures while the second mentioned layer still is in a liquid state in such a manner as to extend the liquid 15 wood into the apertures of the outer shell thus forming a solid unit of the two shells when it has set and filling eventual gaps appearing between the inner shell of liquid wood and the outer main shell with resin, whereby the 20

resin or the like adheres to the inner shell on 25 the one hand and extends into the apertures of the outer shell on the other hand.

3. An artificial limb or the like consisting of a solidified layer of liquid wood the inner shape of which corresponds to the outer shape 30 of the body portion said layer being connected with a main shell of a suitable material and an intermediate layer of liquid wood applied to said first named layer and extending into apertures provided on said main shell.

35 4. An artificial limb or the like consisting of a solidified layer of liquid wood the inner shape of which corresponds to the outer shape of the body portion said layer being connected with a main shell of a suitable material and an intermediate layer partly consisting 40 of liquid wood and partly of resin applied to said first named layer and extending into apertures provided on said main shell.

45 In testimony whereof I have affixed my signature.

JULIUS LOTH.
